UNITED STATES PATENT OFFICE.

EDMUND MÜLLNER, OF BERLIN, GERMANY, ASSIGNOR TO ERICH HUTH, OF BERLIN, GERMANY.

PHOTOGRAPHIC RECORDING APPARATUS FOR GALVANOMETERS, OSCILLOGRAPHES, AND THE LIKE.

1,054,598.

Specification of Letters Patent. Patented Feb. 25, 1913.

Application filed April 4, 1910. Serial No. 553,437.

To all whom it may concern:

Be it known that I, EDMUND MÜLLNER, subject of the Emperor of Austria-Hungary, residing at 39-40 Kottbusser Ufer, Berlin, Germany, have invented new and useful Improvements in Photographic Recording Apparatus for Galvanometers, Oscillographs, and the Like, of which the following is a specification.

10 This invention relates to photographic apparatus for galvanometers, oscillographs and the like and has for its object to improve such apparatus by supplementary devices and means, which are hereinafter described and particularly defined in the claims.

Referring to the accompanying drawing:—Figure 1 is a side elevation, and Fig. 2 a plan view of the whole apparatus, Fig. 20 3 is an end elevation—as seen from the right with respect to Figs. 1 and 2—which represents the photographic recording apparatus, the front wall of the case being removed, Fig. 4 is an elevation of a portion 25 of Fig. 3, Fig. 5 is a diagrammatic view showing the mirror interposed between the objective and photographic lens. Fig. 6 is a perspective view of one of the vessels employed for containing the developing 30 and fixing solutions.

The improved recording galvanometer is based on the known principle of the controlling influence of a light wire or conducting fiber suspended in the magnetic field of an electromagnet. It is known that owing to the sensitiveness of the instruments of this type, they may not only be used for scientific purposes (for indicating the most feeble currents) but also for purposes of wireless telegraphy (as auxiliary recording instruments).

In Figs. 1 and 2, the poles of the galvanometric electromagnet *b* are designated *p* and *q*; the wire or fiber is suspended between the poles at *a* or in the axis between an upper set screw *a'* and a lower set screw *a''*, the said wire or fiber receiving the current to be recorded; it is adapted to indicate owing to its deflection in the magnetic field. In the event of the apparatus being employed as a receiving instrument for wireless telegraphy, the galvanometer fiber

is in circuit with a thermo-electric couple, which serves as the receiving relay of the system. The transmitted feeble current impulses forming the signs are rendered perceptible by the passage or flow of current causing a deflection of the fiber for the respective period. In order that the optical projecting apparatus may render this adjustment of the fiber accessible for direct observation as well as for photographic recording, it consists of the arrangement shown diagrammatically in Fig. 5. A small glow lamp *g* is provided immediately behind the fiber *a* in a holder or socket *f* (Fig. 1) belonging to a folding part *k* of the one pole *p*. The projection of light together with the formation of a shadow of the fiber is effected through an oppositely located object-lens *o* at the end of the optical tube *t*, which has at the other end a cylindrical lens *c* in order to enlarge the image on the exposed part of the strip *s* of sensitive paper; by means of the hereinafter described apparatus, the said strip of sensitive paper is moved past the narrow gap of the screen *x*, where the photographing takes place. As the optical tube *t* forms a kind of microscope, a plane mirror *m* 80 formed of two parts is inserted in the path of rays, as shown in Fig. 5. The two parts of the mirror *m* lie in a plane, which is preferably inclined at an angle of 45° toward the axis of the path of rays. Consequently, the upper and lower part of the image of the fiber is reflected at an angle of 90°. This reflected image will be observed on the screen *n*. This arrangement, besides permitting simultaneous observation and recording, has also the advantage that for the purpose of photography, the direct path of rays is employed, which possesses a greater luminous intensity than the reflected rays, and which reproduces that part of the fiber which is deflected the most. As already stated the small glow lamp *g* is mounted in a holder or socket *f*, which is carried on the one pole piece *p* by means of a hinge-like movable part *k*, whereby it is possible to periodically fold out the lamp and accurately adjust the same. Moreover, the position of the fiber or its utility can be suitably controlled.

Adjusting means for bringing the fiber in a proper position for the adjustment of the objective and for adjusting the field of observation on the optical tube are provided 5 in combination with the apparatus in the known manner.

The photographic recording apparatus is inclosed in a box or case *d*, which is light-tight but permits the renewal of the paper 10 tape spool *r* which is coiled out of sensitive paper. The paper tape *s* runs off the spool *r* and over rollers 1, 2, 3, 4, 5, 6 and 7, whence it passes outwardly to the part *z* (Figs. 1 and 2). The rollers 6 and 7 are 15 coacting presser rollers, the roller 7 being fixed on the shaft of the worm wheel *j* and positively rotated, while the roller 6 revolves reversely to roller 7 and is rotated from the latter. The rollers 6 and 7 serve 20 to strip the tape from the reel *r* and draw it through the machine. The path of the paper tape *s* is shown in Fig. 3, it being assumed that the back wall of the light-tight case is removed. The sensitized paper 25 tape passes the field of exposure at *x*, over the roller 2, the point *x* being the end of the tube *t* where the tape receives the image of the fiber *a*. The two rollers 3 and 5 pass the exposed paper downward successively 30 through the developer and through the fixing liquid. For this purpose, two vessels *u* and *v* are provided within the case containing the recording mechanism. These vessels are of the self supply type and as shown 35 in Fig. 6 each consist of a closed portion 7 communicating with an open spout branch 8 through an opening 9. The opening 9 is of less area than the opening 10 and thus a constant level of liquid is maintained in 40 the spout 8 the portion 7 acting as a storage chamber. An economical supply of fresh liquid to that quantity utilized in the short branch is attained and the large quantity of liquid stored in the long branch re- 45 mains practically uninfluenced by the liquid in the other branch. Both vessels *u* and *v* are adapted to ascend and descend simultaneously. In the descending position—according to Fig. 3—the guide rollers 3 and 5 are 50 situated above the liquid level *y* in the short branch of *u* and *v*. Any suitable mechanism may be employed for raising the vessels; according to the drawing, it comprises a shaft *h* provided with hand-crank *h'* and 55 eccentric cam disks *w w*. As the vessels *u v* are raised into the position according to Fig. 4 by turning the hand-crank *h'*, the lengths of the paper tape *s* passing around the rollers 3 and 5 immerse on both sides in 60 the liquid of the vessels. First of all, the development takes place at *u* and then the fixing of the photographic image at *v*. The paper tape shows, when it passes out of the case *d* at *z*, the photographic reproduction

of the shadow of the deflected fiber in the 65 form of a bent or crooked line on a dark ground. By refixing and watering, the paper tape may be rendered more suitable for preserving the legibleness of the signs.

The driving of the recording mechanism 70 for the feed of the paper tape may be effected by a suitable motor or by clockwork. In the example shown, an electromotor *e* is assumed as the source of power, which acts by means of worm *i* and worm wheel *j*. 75 The disk 8 fixed on the shaft of the motor *e*, forms in combination with the electromagnets 9 an alternating current brake by means of which the load on the motor is kept constant, so that the influence of any 80 sudden fluctuations of revolution of the motor are practically obviated.

Suitable drying means may be provided at the end of the paper tape.

Having now particularly described and 85 ascertained the nature of my said invention and in what manner the same is to be performed, I declare that what I claim and wish to secure by Letters Patent is:—

1. In an apparatus of the character set 90 forth, the combination with the means for detecting wave deflections and a source of illuminant in proximity thereto, of an optical tube adapted to enlarge the image produced by the detecting means, means for feeding a recording tape across the path of said tube, means for projecting the image onto the recording tape and means for developing and fixing the image on the tape.

2. In an apparatus of the character set 100 forth, the combination with the means for detecting wave deflections and a source of illuminant in proximity thereto, of an optical tube adapted to enlarge the image produced by the detecting means, a bi-part mirror in said tube, and a screen upon which the image is reflected and from which direct 105 readings may be had.

3. In an apparatus of the character set 110 forth, the combination with the means for detecting wave deflections and a source of illuminant in proximity thereto, of an optical tube adapted to enlarge the image produced by the detecting means, a bi-part mirror arranged at an angle in said tube where- 115 by the image is projected through the gap between the parts of the mirror, means for feeding a recording tape across the path of said tube, and means for developing and fixing the image on said tape.

4. In an apparatus of the character set 120 forth, the combination with the means for detecting wave deflections and a source of illuminant in proximity thereto, of an optical tube adapted to enlarge the image produced by the detecting means, means for feeding a sensitized tape across the path of the optical tube, and a plurality of auto- 125

matically reciprocable vessels containing developing and fixing fluids wherein the image on the tape is developed and fixed.

5. In an apparatus of the character set forth, the combination with the means for detecting wave deflections and a source of illuminant in proximity thereto, of means for enlarging the image produced by said detecting means, means for feeding a sensitized tape adapted to receive said image, vessels containing fluids for developing and

fixing the image on said tape, and means whereby said vessels are moved to immerse the tape during the feeding thereof.

In testimony whereof I have signed my name to this specification in the presence of two subscribing witnesses.

EDMUND MÜLLNER.
